UNITED STATES PATENT OFFICE.

NICHOLAS E. GIBSON, OF CHICAGO, ILLINOIS.

PAPER-STAPLING MACHINE.

1,048,522.

Specification of Letters Patent. Patented Dec. 31, 1912.

Application filed December 27, 1910. Serial No. 599,348.

To all whom it may concern:

Be it known that I, NICHOLAS E. GIBSON, a citizen of the United States, residing at Chicago, in the county of Cook and State 5 of Illinois, have invented certain new and useful Improvements in Paper-Stapling Machines, of which the following is a specification.

My invention relates to improvements in 10 paper-stapling machines and provides a simple, durable, and efficient mechanism whereby a single reciprocation of a prime mover or handle may result in the cutting of an appropriate length of wire from a continuous strand, the formation of such wire into a staple, the insertion of such staple into an appropriately positioned paper-body or the like, the clenching of the staple, and an automatic feeding of the wire to 20 present a fresh staple-length thereof to be cut and formed by the next succeeding operation of the mechanism.

In the drawings, wherein I have illustrated an embodiment of my invention in 25 a small hand-operated stapling device: Figure 1 is a front elevation with the cover part removed. Fig. 2 is a plan view with parts in section; Fig. 3 is a vertical section on line 3—3 of Fig. 1; Fig. 4 is an enlarged detail, 30 showing in perspective in disassembled relation, several of the plunger parts; and Fig. 5 is a sectional detail on line 5—5 of Fig. 1.

In the drawings, 10 indicates in general a frame casting comprising a base 11 bearing 35 an anvil 12, and a flat web or arm 13 at one end merging into the base, and at its opposite or head end overhanging and spaced apart from the anvil 12. The anvil 12 carries a work plate 14 screwed thereto and 40 also supports a removable forming die 15, located in an appropriate recess and having its upper surface appropriately grooved as at 16 to deflect toward each other the ends of the staple in well known manner.

Above the anvil 12 there is mounted, on 45 the end of the arm 13, a head block, 18, providing left and right side walls 19 and 20 and a rear wall 21, secured to arm 13 as by screws 22. The guide way between the 50 aforesaid head walls is overlain in part by a front plate 23, secured to the head-block as by screws 24 and in the rectangular guide-way thus encompassed works a two-piece plunger mechanism, 25. Specifically, 26 indicates the plunger element constituting the

reciprocating cutting and bending instrumentality, or "shaper member" channeled vertically as at 27 along its rear face, the right-hand side wall of the said member providing near its lower edge a cutter blade 28 and the opposite side-wall carrying a spring-depressed gage pin 29, projecting from socket 30 through the bottom of said side wall and normally maintained against its lower limitation stop 31, by a spring 32 seated between the gage pin and the end of the socket 30. Normally to sustain the shaper member of the plunger in raised position, I provide within the face plate 23 vertical spring recesses 33, in which are disposed extension springs 34, each engaging a pin 35 at the top of the recess and a pin 36 upon the shaper member 26.

Within the vertical guide recess 27 of the shaper member 26 of the plunger is slidably 75 mounted the "driver member" thereof, numbered 37, and consisting of a rectangular driving head 38 with a stem extension 39 to which is attached the prime mover, in the present instance a handle 40 appropriately 80 shaped to receive impacts of the operator's hand. The driver head 38 is capable of an amount of vertical movement relative to the shaper member defined by a pin 41 on the front face of the driver head playing in a 85 slot 42 in the shaper member and the driver member is held normally raised relative to the shaper member by a spring 43, at one end bearing under the handle 40 and at its other end bearing on a collar 44 slidable on 90 stem 39 and resting upon the top of the shaper member 26.

In the right wall 20 of the head block 18, is mounted an annular die or stationary shear member, 45, having its central opening forming part of a wire guide path 46 through which a wire A may be fed until its end abuts against the left wall 19 of the head block, to lie immediately below the cutter knife 28 when the shaper member is 100 in raised position.

In its functional operations the shaper member co-operates with a saddle member 47 preferably in the form of a lever having an elongated stem 48 and a forwardly projecting head 49, having an inclined cam surface 50 and a transverse wire-receiving groove 51 cut inwardly and downwardly from its front edge. An elongated, vertical slot is made in the back wall 21 of the head 110.

block 18, and in it said saddle lever is pivoted on a pin 53 in such fashion that the upper end of the lever normally contacts with and is stopped by the front surface of the frame arm 13, in which position the head of the lever projects into the slideway for the plunger and the front recess 51 of the saddle alines with the wire guide 46, so that a wire inserted through said guide 10 may pass through the recess 51 and lie just back of the guide pin 29. The saddle member is yieldingly pressed to the aforesaid position by a leaf spring 54, mounted upon housing plate or cap 55, secured to the back of arm 13.

In the operation of the device this saddle 47 holds the wire while the shaper member in its descent shears the wire at the die 45 through the operation of knife 28, and continues to hold the wire while the shaper member, performing its bending function, bends the legs or extremities of the wire sharply downward over the sides of the saddle to form a U-shaped staple. The saddle 25 preferably interfits neatly with the side-walls of the cutter member and the inner faces of said walls are, therefore, preferably channeled, as at 57, neatly to receive the wire. Obviously, however, when the driver 30 member of the plunger performs its driving function, the saddle member must be moved out of its path, and to this end, the lower extremity of the driving member is provided with a curved corner 58, to act upon the cam surface 50 of the saddle member to move the head of the latter rearwardly into recess 52 against the tension of spring 54 as the driver member is in descent.

The last described operation presupposes 40 a movement of the two plunger members in unison until the shaper member has performed its function, and then a further depression of the driver member, sliding it downwardly relative to the shaper member. 45 In order that a single depression of the prime mover 40 may thus occasion a depression of both plunger members in unison until the shaper member has performed its function, and then occasion the further depression 50 of the driver member to perform its driving function, I provide means for co-operation between the shaper and driver members to transmit movement from the driver member to the shaper member during a 55 portion only of the range of movement of the driver member. To this end, I provide for temporarily locking the two members of the plunger together by a lever member 60 suitably arranged to receive motion from 60 the driver member of the plunger during a portion only of its stroke, and to impart said motion to the shaper member. Specifically, lever 60 is of bell-crank construction, mounted on a pivot pin 61, in the upper rear 65 corner of slot 52 in the head block 18 to

stand normally with its pendent arm 62 substantially vertically positioned by a leaf spring 63, mounted on the rear face of the frame arm 13 and projecting through a suitable aperture 64 in said arm; the horizontal arm 65 of said bell crank under such conditions extending forward to engage both members of the plunger. The portion of said lever arm 65 which receives motion from the driver member of the plunger, I 75 will term its receiving-nose 66, and the portion thereof which delivers motion to the shaper member of the plunger I will call its delivery-nose 67. The receiving-nose 66 is preferably curved on its upper surface, as 80 best shown in Fig. 4, and stands normally engaged in a recess 69 in the rear face of driver head 38, said recess opening into an elongated depressed channel 70 formed in said rear face of said head. The delivery 85 nose 67 has its lower extremity appropriately shaped to coact with a shoulder 72 forming the bottom of a recess 73, made in the left side wall (right of Fig. 4) of the shaper member, so that when the driver 90 member is depressed the upper surface of its recess 69 acts upon the receiving nose 66 to tilt the bell crank lever 60, depressing the horizontal arm 65 against the tension of spring 63 acting on the vertical arm 62. 95 Consequently the vertical component of movement imparted to the receiving nose 66 is transmitted through the delivery nose 67 to the shoulder 72 of the shaper member, and the driver member and shaper member 100 descend in unison until the receiving nose 66 slips into the channel 70, and rides on the front surface thereof, leaving the extremity of delivery nose 67 resting idly upon the shoulder 72 of the shaper member. 105 The proportion and shape of the parts is such, of course, that the lower end of the shaper member is brought down to a short distance from the work plate 14,—that is, sufficiently far to perform its intended functions, before the receiving nose 66 slips into the channel 70.

The feeding mechanism for delivering the wire is arranged for automatic operation in appropriate timed relation to the movements of the plunger parts and preferably comprises primarily a vibrating feed dog, which is moved by the plunger against spring tension to condition it for operation, is automatically locked in such position, and 115 is tripped automatically by the plunger at the extreme end of the plunger up-stroke, thereby to release the feed dog for a spring actuated feeding movement. Specifically, 120 75 indicates a wire holding stud on the arm 13 provided with a detachable retaining head 76, screw-threaded thereinto and receiving the coil of wire A the end of which is led through the feeding mechanism and 125 through the wire guide 46. To prevent ac- 130

cidental retraction of the wire from said guide 46, I provide on the right side of the head block 18 a lug 77 having a guiding aperture 78, through which the wire is led to lie upon the top surface of the lug 77 and be acted upon by a retaining pawl 79, pivoted to a suitable stud 80, and having its toothed lower surface pressed by spring 81 against the wire in position to clamp it against retraction, but to accommodate the forward feeding operations of the wire. The vibrating feed member preferably comprises a lever 83, pivoted as at 84 upon the arm 13, said lever providing a horizontal projection 85 and a vertical leg 86, provided between its ends with a lateral spur 87 and at its lower extremity having a foot plate 88 presenting at its end an apertured guiding offset 89. Against the foot 88 works a pawl 90 pivoted as at 91 to the leg and having its toothed lower surface yieldingly depressed by a spring 92 to clamp the wire for the forward feeding operation but to slip easily along the wire in direction toward the wire supply. A long coiled spring 93 at one end attached to the spur 87 and at its other end to a pin 94 serves to actuate the vibrating feed member on its forward or feeding stroke. The projection 85 of said 30 vibrating lever extends through an elongated slot 95 made therefor in the side wall 20 of head block 18 and its tip extends into an aperture 96 in the side wall of the shaper member of the plunger to lie directly in the 35 path of reciprocation of the shoulder 97, the proportions of the parts being such that while the shaper member is being depressed, shoulder 97, acting on the tip of the projection 85, moves the lever 83 to the full extent of its intended retraction, which is limited by a stop pin 98 upon the frame. To latch the vibrating lever in this position of retraction I provide a vertical latch dog 100 disposed in a slot 101 in the rear wall of the 40 head block 18 and mounted upon the pivot pin 53. Said latch dog 100 is provided with a latching nose 104, positioned to overlie the tip of the projection 85 when the latter is depressed, and is also provided with a lower 45 cam surface 105, for coaction with the surface 106 at the bottom of the slot 96 in shaper member 26 of the plunger. Springs 107 working against the rear side of the dog 100 tend to press the latter forward into the 50 path of the projection 85 of the feed lever, so that when the projection is depressed the latch nose 104 engages its upper surface and restrains it against return to original position until the shaper member of the plunger 55 has completed substantially its entire up stroke and its surface 106 strikes the cam projection 105 of said dog and forces the dog back into its recess 101 against the tension of springs 107, thereby to release the feed 60 lever for spring-return under the influence of spring 93 to normal position, so to effect a feeding operation upon the wire A. The precise extent of feeding throw of the feed lever is regulated by adjustment of a screw 108 which acts as a stop to limit the upward movement of lever projection 85. 70

As a refinement in the machine, I preferably provide means for insuring a complete reciprocation of the prime mover each time it is depressed, thereby to prevent such partial operations of the machine as would result in short-cut, mutilated, or partially folded staples. With this end in view, I provide on one side of the driver body 38, a vertical rack 110, with terminal switch recesses 111 at its ends, and on the face plate 23 I pivot a switch pawl 112 playing through the slots 95 and 96 in the head block 18 and shaper member 26, so that the toe of the pawl may stand normally in the 75 lower switch-recess 111, below the rack 110. A pawl spring 113 connected between the tail of the pawl and a spring post 114 on the base plate serves normally to hold the pawl with its toe horizontal, but it will be 80 apparent from Fig. 1, the pawl will act as a means to prevent reversal of movement of the driver member at any time save at the opposite extremities of the stroke, when the toe of the pawl enters one of the switch 85 recesses 111. 90

Now, it will be apparent that the operation of the machine specifically described is briefly as follows: The machine is threaded with wire and normally stands with the 100 parts in the positions shown in Fig. 1, the wire passing through the guide 46 across the saddle recess 51 to abut against the remote wall of the head block 18. Now, the material to be stapled is inserted in the 105 space between the head block 18 and the work plate 14. The prime mover or handle 40 is depressed generally by a sharp blow, with sufficient force to drive the reciprocating driver part to its lowest limit of travel. 110 The resultant downward movement of the driver member of the plunger acts upon the receiving nose 66 of bell crank lever 65, and the delivery nose 67 thereof acts to move the shaper member 26 downward against the 115 tension of springs 34, so that its shear 28 severs the wire at the stationary shear member 45, and its side members bend the wire length so cut around the saddle 47 into U-shape, the legs of the staple lying in the 120 slots 57 in the side walls of the shaper member. Such downward movement of the shaper member likewise forces down the feed lever projection 85, throwing the foot 88 outward and upward along the wire, 125 against the tension of spring 93, so that the feed pawl 90 takes a fresh grip upon the wire at an elevated point and as the feed lever projection 85 reaches its depressed position nose 104 of latch 100 engages and 130

locks it. When the cutting and bending functions of the shaper member of the plunger have been performed, the receiving nose 66 of the connecting lever 65 rides in groove 70 of the driver member of the plunger so that the only moving connection subsequently existing between the two plunger members is that effected through the spring 43. Consequently, the shaper member bottoms upon the material emplaced upon the work plate 14 but the driver member continues to descend compressing the spring 43. When the surface 58 of the driver member strikes the cam surface 50 of the saddle member 47, the latter is pressed rearwardly into its recess against the tension of spring 54, releasing the staple and leaving it standing with its legs upon the material to be stapled, and guidingly maintained by the recesses 57 in the shaper member of the plunger. Thus, when the driver member contacts with the transverse or yoke portion of the staple, the legs are driven through the material on the work plate until the ends of the legs meet the forming die plate 15, and by reason of the contour of the recess 16 therein, are turned inwardly so that when the driver reaches the bottom of its travel, the staple is completely closed. It will be observed, that when once the driver member starts in its descent the nose of the switch pawl 112 turns downwardly and coacts with rack 110 to hold the driver member against retraction. When the bottom of the down-stroke is reached the switch pawl slips into the upper switch recess, and as the back stroke of the driver commences the pawl is switched to present its nose upwardly, thereby to act to prevent a second operation of the device until the parts have all been restored to normal position. On the up-stroke of the plunger the driver member rises under the tension of its strong spring 43, until the stop pin 41 engages the end of slot 42, and the weaker springs 34 lift the shaper member back to its normal raised position. Just before the shaper member reaches its normal position its surface 106 acts upon cam surface 105 of holding pawl 100 for the feed lever to press the holding pawl back into its recess, releasing the projection 85 of the feed lever, so that said lever is spring-retracted to normal position, the adjustment of stop screw 108 being such that just enough wire is fed forward through the path 46 to bring its extremity into contact with the opposing wall of the head block; slot 51 in the saddle and guide pin 29, both exerting a guiding effect to insure the proper emplacement of a fresh staple-length of wire for the succeeding stapling operation.

While I have herein described in some detail a specific embodiment of my invention it will be apparent to those skilled in the art that numerous changes in the construction

employed might be made without departure from the spirit of my invention and within the scope of the appended claims.

What I claim is:

1. In a machine of the character described, 70 a head frame providing a guideway and a space confronting said guideway, a two-piece plunger working in said guideway comprising a driver member and a shaper member, a prime mover connected with said driver member, and a lever mounted on a transverse pivot in said space within the head frame, said lever lying wholly within said space confronting the driver and shaper members and provided with oppositely disposed nose portions coöperating with the respective members of the plunger, and imparting motion from the driver member to the shaper member during a portion only of the travel of the driver member. 75

2. In a hand-operated stapling machine, 80 the combination of a channeled frame, a channeled shaper vertically reciprocable therein, a driver member slidable in the channel of the shaper member, a handle-stem above and connected to the driver member, a spring surrounding said stem for connection between the driver and shaper members, said driver and shaper members having like faces provided with opposing shoulders, 90 and a wide lever, 63, pivoted on an axis parallel with said faces and providing oppositely facing nose portions, within the width of the lever, arranged to coact with the opposing shoulders on said members, substantially as described. 100

3. In a hand-operated stapling machine, 105 the combination of a head frame; a shaper member channeled throughout its length, extending above said frame, and slidable in said frame; a driver member slidable in the shaper member; a handle-stem above and connected to the driver member; a spring surrounding the said stem, for interposition between the driver and shaper members; 110 means for connection of the driver and shaper members during a portion only of the stroke of the driver member; spring means for restoring the shaper member; an anvil coöperating with the driver member at the 115 end of the stroke, and a saddle normally extending into the channel of the shaper, and movable automatically to escape from the path of the driver. 120

4. In a hand-operated stapling machine, 125 the combination of a head frame; a shaper member channeled throughout its length, extending above said frame, and slidable in said frame; a driver member slidable in the shaper member; a handle-stem above 125 and connected to the driver member; a spring surrounding the said stem for interposition between the driver and shaper members; a lever pivoted to the frame, movable by the driver member and moving the 130

- shaper member during a portion only of the stroke of the driver member; spring means for restoring the shaper member, an anvil coöperating with the driver member 5 at the end of its stroke; and a saddle normally extending into the channel of the shaper member and movable automatically to escape from the path of the driver member.
- 10 5. In a hand-operated stapling machine, the combination of a head frame having a guideway and a confronting space therein, a channeled shaper member slidable vertically in the guideway of said frame, and 15 extending thereabove, a driver member slid- able in the shaper member, like faces of the driver and shaper members being provided with opposing shoulders, a handle stem above and connected with the driver mem- 20 ber, a spring surrounding said stem inter- posed between the driver and shaper mem- bers, and a spring-pressed latch lever mount- ed in said head space confronting the shoul- 25 dered face of the driver and shaper mem- bers and providing, as a continuation of the body of the lever, nose portions for coac- 30 tion with the opposing shoulders of said members, to receive motion from the shoul- der of the driver member and communicate it to the shoulder of the shaper member.
6. In a hand stapling machine, the combination of a frame providing a head and an anvil therebelow, a channeled shaper 35 slidable in the head and extending there- above, a driver slidable in the channel in said shaper, said shaper and said driver having shoulders on corresponding faces; a handle extending upward from the driver, a spring surrounding said stem acting on 40 the driver and shaper, a spring connection between a stationary part of the head and the shaper; a bell-crank lever pivoted on the frame coacting with the shoulder on the driver and shaper to receive movement from 45 the former and communicate it to the latter, a spring acting on the other arm of said lever; and a saddle normally lying in the shaper channel and movable out of the path of the driver.
- 50 7. In a hand-operated stapling machine, the combination of a guiding frame, a chan- neled shaper member vertically slidable in the frame, a vertically reciprocable, driver member, slidably arranged in the channeled 55 shaper member, said driver member having

therein a rack provided at its ends with switch recesses, and a pawl pivoted on the frame, coöperating with said rack and switch recesses, substantially as described.

8. In a stapling machine, the combination 60 of a frame, providing a base, an anvil, and an arm overhanging the anvil, and a guid- ing head upon said arm, a two-piece plunger guidedly supported in said head, and comprising a driving member and a shaping 65 member, a prime mover for said driving member, means for connection of said shaper member to the driver member for actuation thereby, wire guiding and supporting means upon said head, wire-reeding means upon 70 said arm including a vibrating feed lever moved to set position by the plunger, and a latch arranged to hold said arm in set position, arranged for release by the plunger.

9. In a stapling machine, the combination 75 of a frame providing a base, an anvil, an arm overhanging the anvil, a guiding head upon said arm, a two-piece plunger guidedly supported in said head, and comprising a driver member and a shaping member, a 80 prime mover for said driving member, means for connection of said driving member with the shaping member, for actuation thereof, wire guiding and shaping means upon said head, wire-feeding means upon 85 said arm including a vibrating feed lever, a spring for effecting the feeding movements of said lever, means operable by the plunger to condition said lever for its feeding move- 90 ment, a latch for holding said lever against the tension of said feed spring, and means upon said plunger for releasing said latch.

10. In a hand-operated stapling machine, a frame providing a head, an arm, and a base, the head having a face plate and an 95 interior guideway; a channeled shaper mem- ber slidable in the guideway, springs con- necting the face plate and shaper member; a driver member slidable in the channel of the shaper member, said driver having a stem 100 and a handle thereon, a collar surrounding the stem and bearing on the shaper member, and a spring member between said collar and handle.

In testimony whereof I hereunto set my 105 hand in the presence of two witnesses.

NICHOLAS E. GIBSON.

In the presence of—

W. LINN ALLEN,
GEO. T. MAY, Jr.
